UNITED STATES PATENT OFFICE.

WILLIAM S. TOTHILL, OF CHICAGO, ILLINOIS.

TEETER DEVICE.

1,418,037.

Specification of Letters Patent. Patented May 30, 1922.

Application filed March 21, 1921. Serial No. 453,936.

To all whom it may concern:

Be it known that I, WILLIAM S. TOTHILL, a citizen of the United States, and a resident of Chicago, in the county of Cook and State 5 of Illinois, have invented certain new and useful Improvements in Teeter Devices, of which the following is a specification, reference being had to the accompanying drawings.

10 This invention relates to teeter devices wherein the pivoted member is usually in the form of a ladder or framework, from the opposite ends of which two children that grasp such ends are alternately raised. 15 from the ground, and it is in connection with a device designed to be so used that my improvements are associated in the structure shown, although it is to be understood that said improvements may be equally well employed in connection with that form of teeter devices wherein the users sit upon the ends of the pivoted member referred to instead of hanging therefrom.

It is the leading object of my invention 20 to provide a device of the general character mentioned with means for preventing injury to one of the users if the other user suddenly releases his hold or removes his weight from the pivoted ladder or framework, and 25 I accomplish this by providing improved cushioning means, as hereinafter particularly described, that are interposed between such pivoted member and its support.

In the drawings:

30 Fig. 1 is a plan view of a teeter device embodying my improvements;

Fig. 2 is a side view thereof;

Fig. 3 is an enlarged sectional view, partly broken away, taken on line 3—3 of 35 Fig. 1;

Fig. 4 is a cross-section taken on the line 4—4 of Fig. 3, and showing the manner of mounting the ladder on the supporting device; and

40 Fig. 5 is a detail of the connection between one of the tension springs and the plug at the upper end thereof, and showing also the lower end of the rod that passes through such plug.

45 Referring to the drawings,—10 indicates a supporting standard which preferably is formed from a piece of heavy tubing as shown. When the device is erected out of doors, as it usually will be, such supporting standard may well be held in position by 50 having its lower end embedded in a cement

foundation, as shown in Fig. 2. The manner of securing such standard in an upright position, however, may be accomplished in any usual manner. Slidably mounted upon 60 this standard is a heavy cylindrical head 11 which is adjustably secured at any desired height by means of a bolt 12 passing through said head and through any one of a series 65 of holes in the standard. Near the upper end of the head and at diametrically opposite sides thereof are formed two upwardly-extending arms 13 that extend above the upper end of the head 11 and in effect together form a yoke to which the oscillating or 70 teeter member of the device is pivotally attached. This oscillating or teeter member is indicated generally by 14, and, in the form of construction shown, is of ladder-like 75 design, viz, it comprises two long side bars connected together at intervals by cross-bars, and, by reason of such construction, this member is ordinarily termed in the trade a ladder and will be so referred to herein, although it is to be understood that the ladder-like construction referred to may be varied 80 from without departing from my invention. The ends of the side-bar members of this ladder are appropriately shaped, as indicated in Fig. 2, to furnish suitable hand holds for the users to grasp and hang suspended from. The ladder 14 is of such width as to have the inner faces of its side bars lie alongside of the outer faces of the 85 yoke arms 13, and it is pivotally connected 90 with such yoke arms by means of pivot pins 15, as best shown in Fig. 4, and as shown in said figure each of the pivot pins may be locked in place by a set-screw 16. Near the lower end of the head 11 and projecting 95 therefrom in opposite directions are two short arms 17 each of which carries a comparatively long sleeve 18 that is located at such an angle to the head 11 as to bring the lower end of the sleeve considerably 100 closer to the standard 10 than is its upper end. The head 11, the yoke arms 13, the arms 17 and the sleeves 18 are preferably 105 formed integral with each other as indicated, and the arms 17 extend out at a right angle to the vertical plane of the yoke arms 13 so that the upper ends of the sleeves 18 will be directed substantially toward the longitudinal center of the ladder member 14. Within each of the sleeves 18 is located 110 a coiled expansion spring 19 that is held therein by the engagement of its lower coils

with the screw-threaded portion of a plug 20 that is inserted in such lower end and held therein by a pin 21 or otherwise. In the upper end of each sleeve 19 is located another plug, indicated by 22, which, like the plug at the lower end, has a screw-threaded portion upon which the coils at the other end of the contained spring 19 are secured. This upper plug, however, is not secured to the sleeve as is the lower plug, but on the contrary is free to move out of the sleeve during the operation of the device. Through each plug 22 extends a rod 23 that on its lower end is provided with any suitable device that, by contact with the lower end of the plug through which it passes, will be prevented from being pulled out of such plug and when an upward pull on the rod is had will cause the plug to expand its attached coiled spring 19 and thus draw it partially out of its containing sleeve. The upper end of each rod 23 is formed with an eye which encircles a short transversely-arranged bolt 24 carried by the ladder member 14. As shown, each rod 23 extends through an opening in a transverse bar 25 that is bolted to the side bar members of the ladder 14, and interposed between the top of the cross-bar and the pivot bolt 24 is a metal washer 26. The openings through the cross-bar 25 and its washer are to be wide enough, of course, so that no binding of the rod by contact with the cross-bar or washer will occur during the oscillation of the ladder member 14. Upon the upper end of each sleeve 19 is mounted a heavy coiled spring 27 which will act as a buffer in case the ladder member is turned sufficiently to bring the cross-pieces 25 down that far.

In operation the head 11 will be adjusted to the desired height on the standard 10 and the hand holds at the ends of the ladder member will then be grasped by two children and such ladder member oscillated on its pivot pins 15 in the usual manner, and, of course, during such oscillation the rods 23 will alternately pull on their respective attached coiled springs 19, and each will, therefore, act to not only limit the upward movement of its end of the ladder member, but upon the return downward movement will settle back into place in its sleeve and have no effect on the movement of the ladder member because, as will be readily understood, the rod 23 on the downwardly-moving half of the ladder will move freely down through its plug 22. Each of the springs 19, therefore, will act to slow up and to a certain extent cushion the device on the upward movement of that half of the ladder to which it extends, and upon the downward movement of such half such spring 19 will exert a downward pull until the ladder has reached a substantially horizontal position, as indicated in Fig. 2, and thereafter the

downward movement will be resiliently checked or slowed up by the putting under tension of that spring that is at the half of the ladder that is then moving upwardly.

By reason of the construction and arrangement of the two springs 19 it will be apparent that the liability of injury to the apparatus, and, what is more important, liability of injury to the children using the device, will be very largely eliminated. For example, if the child at one end drops off of his end of the ladder when such end is lower than the other the ladder at the other end can only descend to a substantially horizontal position before the coiled spring 19 that is at that end of the ladder from which the child dropped off will function and the other half of the ladder that the other child is on will thereby be caused to descend much more gradually. Furthermore, if in such case the weight of the child remaining on the ladder is sufficient to cause his end to move far enough down the heavy coiled spring 27 at that side will also act as an additional cushioning means.

While each rod 23 could, of course, be attached to its coiled spring 19 by some other means than the screw-threaded plug shown and the lower end of such coiled spring could be secured in place by means other than the plug 20 that is secured in the lower end of the sleeve, I prefer such constructions not only because they form effective devices for the purpose named, but because they constitute closures—the upper one of the plugs 100 constituting a sufficient closure when the device is at rest to largely prevent the admission of foreign matter, and the lower plug constituting an effective closure that will prevent mischievously-inclined children from 105 interfering with the spring that is within the sleeve and would also prevent them from poking dirt or rubbish into such sleeve.

What I claim as my invention and desire to secure by Letters Patent, is—

1. In a device of the character described, the combination of a support, a head mounted thereon, a teeter device pivotally mounted on the upper portion of said head, arms projecting from opposite sides of said head at substantially right angles to the axis of the pivot of the teeter device, an outwardly and upwardly inclined spring-holding device carried by each arm, and a coiled spring held at its lower end to each of said inclined devices and connected at its upper end to said teeter device.

2. In a device of the character described, the combination of a support, a head mounted thereon a teeter device pivotally mounted on the upper portion of said head, arms projecting from opposite sides of said head at substantially right angles to the axis of the pivot of the teeter device, an outwardly and upwardly inclined tubular member car-

ried by each arm, a coiled spring held in each tubular member, and means connecting each of said springs with said teeter device.

3. In a device of the character described, 5 the combination of a support, a head mounted thereon, a teeter device pivotally mounted on the upper portion of said head, arms projecting from opposite sides of said head at substantially right angles to the axis of 10 the pivot of the teeter device, an outwardly and upwardly inclined tubular member carried by each arm, a coiled spring held in each tubular member, means connecting each of said springs with said teeter device, and 15 a closure member carried by the spring adapted to be moved out of closing position when the spring is expanded.

4. In a device of the character described, 20 the combination of a support, a head mounted thereon, a teeter device pivotally mounted on the upper portion of said head, arms projecting from opposite sides of said head at substantially right angles to the axis of the pivot of the teeter device, an outwardly 25 and upwardly inclined tubular member carried by each arm, an expansion spring held in each tubular member and connected with said teeter device, and a compression spring also supported at its lower end from each 30 of the said inclined members.

5. In a device of the character described, 35 the combination of a support, a head mounted thereon, a teeter device pivotally mounted on the upper portion of said head, arms projecting from opposite sides of said head at substantially right angles to the axis of the pivot of the teeter device, an outwardly and upwardly inclined tubular member carried by each arm, an expansion spring held 40 in each tubular member and connected with said teeter device, and a compression spring also supported at its lower end from each of the said inclined members, each compression spring being of sufficiently large di- 45 ameter to permit the adjacent expansion spring to move through it.

6. In a device of the character described, 50 the combination of a support, a head mounted thereon, a teeter device pivotally mounted on the upper portion of said head, arms projecting from opposite sides of said head at substantially right angles to the axis of the pivot of the teeter device, an outwardly and upwardly inclined tubular member carried by each arm, an expansion spring held 55 in each tubular member, a rod connecting such spring with said teeter device, and a compression spring surrounding said rod, said compression spring being held in a fixed 60 inclined position to maintain its axis approximately coincident with the axis of the adjacent expansion spring.

7. In a device of the character described, 65 the combination of a support, a head slid- 65 ingly mounted on said support, means for

securing said head in different adjusted positions, a pair of expansion springs connected at their lower ends with said head, one on each side thereof, a teeter device pivotally mounted on the upper portion of said head, means connecting the upper end of each expansion spring with said teeter device, and a pair of compression springs mounted one on each side of said head, whereby the compression spring on one side 70 co-acts with the expansion spring on the opposite side to yieldingly oppose the turning of said teeter device.

8. In a device of the character described, 75 the combination of a support, a head mounted on said support, said head having oppositely-disposed outwardly and upwardly extending members, a teeter device pivotally mounted on said outwardly and upwardly extending members, a pair of expansion 80 springs connected at their lower ends with said head and having their upper ends connected with said teeter device, so that said springs alternately yieldingly oppose the turning of said teeter device. 90

9. In a device of the character described, 95 the combination of a support, a head mounted on said support, said head having oppositely-disposed outwardly and upwardly extending members, a teeter device pivotally mounted on said outwardly and upwardly extending members, a pair of cross pieces 100 on said teeter device one at each side of said support, a pair of oppositely-disposed arms connected to said head at its lower end and extending approximately at right angles to said outwardly and upwardly extending members, a spring mounted on each of said arms, and means connecting one of said springs with one of said cross pieces, and 105 other means connecting the other spring with the other cross-piece, whereby said springs alternately yieldingly oppose the turning of said teeter device.

10. In a device of the character described, 110 the combination of a support, a head mounted on said support, a teeter device pivotally mounted on said head, a pair of cross pieces on said teeter device one at each side of said support, a pair of oppositely-disposed 115 arms connected to said head at its lower end, a sleeve connected with the outer end of each of said arms, an expansion spring mounted in each sleeve, and means connecting the upper end of each expansion spring 120 with one of said pair of cross pieces, respectively, so that said springs alternately yieldingly oppose the turning of said teeter device.

11. In a device of the character described, 125 the combination of a support, a head mounted on said support, a teeter device pivotally mounted on said head, oppositely-disposed arms connected to said head at its lower end, sleeves extending diagonally downward 130

from the outer ends of said arms, a plug connected to the lower end of each of said sleeves, an expansion spring in each of said sleeves connected at its lower end to said plug, a second plug connected to each of said expansion springs at its upper end, and means connecting said last-mentioned plugs with said teeter device whereby said springs alternately yieldingly oppose the turning of 10 said teeter device.

12. In a device of the character described, the combination of a support, a head mounted on said support, a teeter device pivotally mounted on said head, a pair of oppositely-disposed arms connected with said head, a sleeve extending downwardly and inwardly from the outer end of each of said arms, a plug connected to the lower end of each of said sleeves, an expansion spring mounted 15 in each of said sleeves and connected at its lower end to said plug, a plug connected to

each of said expansion springs at its opposite end, and a rod connecting each of said expansion springs with said teeter device at opposite sides of said support respectively, 25 whereby said springs yieldingly oppose the turning of said teeter device.

13. In a device of the character described, the combination of a support, a head carried thereby, a teeter device pivotally supported from said head, two sleeves attached to said head at opposite sides thereof, a coiled expansion spring secured at its lower end in each sleeve, two rods each connected at its upper end with the teeter device and 30 having its lower end extending into one of said sleeves and the coiled spring in said sleeve, and means carried by each spring and rod for causing said springs to be alternately expanded during the operation of 35 the teeter device.

WILLIAM S. TOTHILL.
